(57) **CLAIM**

The ornamental design for a massage table head rest pad, as shown and described.

DESCRIPTION

FIG. 1 is a perspective view of a massage table head rest pad as viewed from the top and front.

FIG. 2 is a top plan view of a massage table head rest pad.

FIG. 3 is a bottom plan view of a massage table head rest pad.

FIG. 4 is a back side elevation view of a massage table head rest pad.

FIG. 5 is a front side elevation view of a massage table head rest pad.

FIG. 6 is a right side elevation view of a massage table head rest pad; and,

FIG. 7 is a left side elevation view of a massage table head rest pad.

The broken lines in the drawings depict portions of the massage table head rest pad that form no part of the claimed design.
